LIQUID DISPENSER EQUIPMENT

Thomas A. Hutsell, Renton, Wash.

Application March 8, 1943, Serial No. 478,349

5 Claims. (Cl. 225—26)

The present invention relates to liquid dispenser equipment and more particularly to a dispenser for mixing a syrup with a carbonated water and dispensing such in measured quantities of both the syrup and the carbonated water.

In the prior art there has been found difficulty in measuring out a medium such as a thick syrup whose viscosity would change with varying temperatures, and of properly mixing such syrup under varying conditions with the carbonated water. If the syrup were to be added to either the first or last part of the water dispensed, the result would be an uneven mixture. Such is not desirable.

Having in mind these defects of the prior art, it is an object of the present invention to design and construct a device that will accurately measure, mix and dispense quantities of syrup and carbonated water.

Another object of the present invention is the measuring out of a quantity of syrup and then of continuously withdrawing parts of the measured quantity of syrup and mixing each of such parts with water until all of the measured amount is withdrawn.

A further object of the present invention is the provision of a liquid dispenser having a mixing chamber and means for continuously adding to said chamber measured amounts of both syrup and water.

Yet a further object of the present invention is the provision of actuating means that allows a dispensing movement of an operating handle or lever and which movement will store energy in the device for completion of the dispensing operation.

The above mentioned defects of the prior art are remedied and the aforementioned objects attained by the construction of a beverage dispenser that has a syrup chamber and an ice chamber with coils therein for carbonated water, which coils may be connected to a suitable source of carbonated water or other mixer. The syrup chamber, or reservoir, has placed therein a pump for removing syrup from the chamber and transferring it to a mixing chamber. The mixing chamber is also connected to the water coils by means of a valve. The piston of the pump is actuated by a spring to dispense the syrup. The spring is compressed by a lever operated linkage, that allows a free return of the piston after it has been compressed. Actuation of the linkage serves to open the valve to let water into the mixing chamber; return of the piston actuates a link to close the water valve. Also, during the return of the piston, a measured amount of syrup is dis-

pensed into the mixing chamber in a continuous stream to mix with the water passing therethrough.

Hereinafter is set forth the details of a device embodying the above outline, which device remedies the defects and attains the objects previously set forth. In the drawings

Figure 1 is a view in elevation of my beverage dispenser, with portions broken away and others shown in section for convenience of illustration;

Figure 2 is a similar view in elevation of my beverage dispenser mechanism similar to Figure 1, but taken in a different plane as indicated by line 2—2 of Figure 3;

Figure 3 is a vertical sectional view through my beverage dispenser on the plane of line 3—3 of Figure 1;

Figure 4 is an exploded perspective view of the pump actuating mechanism employed in my beverage dispenser;

Figures 5 and 6 are similar vertical sectional views of a portion of the actuator mechanism of my dispenser; and

Figure 7 is a vertical sectional view of a valve mechanism within the dispensing spout of my apparatus.

A preferred embodiment of my invention, referring particularly to Figure 3 in the drawings, is constituted by a container base 10 which has a hollow interior forming a chamber 12 in which and on which is mounted the operating mechanism of the dispenser. Within chamber 12 is placed the fluid F to be dispensed. In the fluid I immerse pump cylinder 14. Within cylinder 14 is the pressure chamber 15 having a lower inlet 16 which on occasion is closed by the valve ball 18. Piston 20, in the cylinder, reciprocates to vary the size of chamber 15 and includes the hollow piston stem 22 which is surrounded, within the cylinder, by an expansion spring 24 that operates between the piston 20 and the cylinder head 26 to urge the piston downwardly. Relief ports 28 in cylinder 14 are indicated.

It is intended that the container base 10 be supported upon a superstructure of the conventional soda fountain or bar. For that purpose I provide the clamp 30 which is fitted over an upright wall of such a fountain or bar and clamped tightly thereon by means of set screw

32 to support the dispensing mechanism. On a forward face of the container I provide a ledge or shelf 34 for the accommodation of a drinking glass or tumbler 36 when the mechanism is used for dispensing purposes.

The stem 22 of the piston serves as the dis-

charge outlet of pressurized fluid from below piston 20, as when the spring 24 is urging the piston downwardly against a quantity of fluid trapped by valve 48 in cylinder 14. From stem 22 the fluid flows through a flexible conduit 38, thence to the passage 102 of dispensing nozzle 40 where its discharge is controlled by the adjustable needle valve 42. Valve 42 is shown in Figure 2 as having a pointed end 43 which may be advanced or retracted from the discharge end of conduit 38.

Piston 20 and tube 22 is raised by lever 44 that is fixedly pivoted at 46 to wall 48 of the upper cabinet 50. Cabinet 50 rests upon the container base 10. Lever 44 is pivotally connected at 54 to piston rod 22 by the depending link 52.

Lever 44, intermediate pivots 46 and 54, is joined at pivot 45 to the slide link 56. This link is slotted at 58 to receive the guide pin 60 which limits reciprocal movement of the link to the vertical. Link 56 has a pair of outstanding ears 61 that by pivot pin 62 join arm 63 that is downwardly urged by spring 64. Arm 63 has a horn 66 which is employed in a manner later to be described.

Between bracket arms 70, 70 on the wall of case 50 is pivotally mounted the hand lever 72 that swings on the pin 74. Lever 72, taken with the angularly disposed arm 76, comprises a bell crank which is coupled to arm 63 by the intermediate H-shaped connector link 78. On the end of lever 76 I provide a boss 77 to engage against the lower side of the cross bar of link 78 at certain times during the operation of the equipment. The cross-bar 80 of link 78 has an inclined upwardly facing shoulder 79 with which the horn 66 coacts on certain occasions.

From the initial position shown in Figure 3, swinging movement of the handle 72 and arm 76 will cause the H-shaped connector link 78 and the arm 63 to raise the slide link 56, the horn 66 of arm 63 abutting on the face 79 of link 78 to maintain the arm 63 and link 78 in a past center position. As the swinging movement continues, the boss 77 contacts the under side of cross bar 80, thus effectively forming a rigid link between pivot 74 and pivot point 65. Further movement of the lever 72 will cause the pivot 65 to break over to the opposite off-center position between pivots 81 and 62, which frees arm 63 from exerting further lifting force against the slide link 56 and permits independent downward travel of said link under the action of spring 24.

When lever 72 is swung from the position of Figure 3 to the position of Figure 5, the link slide 56 is raised, causing swinging movement of lever 44 about pivot 46 to raise link 52 and to in turn raise piston 20 against the action of spring 24. Thus a charge of fluid is drawn from chamber 12 into the chamber 15 under the piston cylinder, during which time ball 18 is raised from its seat in the opening 16. The raising stroke of the piston is momentary, and upon reaching its upper limits, is discontinued when the connecting link 78 is broken over to the position of Figure 5, against the tension of spring 64, to permit the piston 20 to descend under the urging of spring 24, irrespective thereafter of the position of lever 72. When lever 72 is manually returned to the position of Figure 3 from that of Figure 6, the dispensing mechanism is set to be again operated to discharge a flow of the fluid being dispensed. During the downward stroke of piston 20, fluid flows through stem 22 and conduit 38 to valve 42 and thence into the mixing chamber of spout 40.

Within chamber 51, in case 50, I mount a cooling coil 90 which has at one end the inlet conduit 92 and at the other end the outlet 94. Conduit 92 is coupled to a conventional carbonated fluid dispenser, usually of the constant pressure type. This carbonated liquid flows through tube 92, coil 90, to outlet 94.

Within chamber 51 is also usually stored a certain amount of liquid and ice, or other coolant, for refrigerating in transit the fluid in coil 90 as it passes through the chamber 51. An overflow tube 96 accommodates such superfluous coolant as may accumulate in chamber 51 and this liquid either drips out of the opening 98 or is otherwise removed as desired.

From outlet 94 the gas-bearing fluid flows to the passage 100 of the dispensing spout 40. Between passage 100 and the mixing chamber or passage 102 is an orifice 103 that is opened or closed by valve 104 which limits the flow of the cooled gas-charged fluid out of the spout 40. Valve head 104 is mounted on a valve stem 106, that reciprocates through gland 108 and has a portion below the spout. On stem 106 is collar 110 and, spaced therebelow is a second shoulder 112, in this case shown as provided by the adjustment nut 114. Between shoulders 110, 112 is disposed flange 116 of draft link 118 connected by pin 45 to lever 44 and link 56 for vertically reciprocal operation therewith. Link 118 is slotted at 119 so that portions of it pass on either side of the shank of spout 40 adjacent where it enters case 50.

Shoulders 110 and 112 and the flange 116 comprise a lost motion action. It will be seen that, when link 56 is raised, link 118 is drawn upwardly so that the flange 116 contacts the under side of collar 110 to raise and open valve 104. It will also be seen that, as lever 44 returns downwardly to its normal position, link 56 is returned downward to its normal "at rest" position. At the same time, link 118 also returns downwardly, during all of which time the valve 104 is open until flange 116 contacts shoulder 112 on nut 114 and closes the orifice between passage 100 and chamber 102. During the interval that orifice 103 is open, the carbonated fluid flows at a fairly constant rate into chamber 102 where it mixes with the syrup, discharging through valve 42. This mixture then is discharged from spout 40 and comprises the drink being dispensed.

During substantially all of the raising stroke of piston 20, at which time the flange 116 that operates valve 104 is also raising, the primary action that takes place is the draft of a charge of syrup F into chamber 15. At or near the end of the upward stroke of the piston, and consequently the upward stroke of flange 116, valve 104 is raised from its seat, thus initiating a flow of the carbonated fluid through orifice 103 into the mixing chamber 102. Simultaneously therewith the piston is released to travel downward under the urging of the spring 24 which initiates a flow of syrup through valve 42. Ordinarily the gas-charged fluid flows at a constant rate under a pressure of approximately five to six pounds per square inch. Due to the pressure of the spring imparted to the piston, the syrup flows at a pressure of from ten to twelve pounds per square inch.

As the syrup is discharged from conduit 38 against the pointed end of the valve needle 42, the action is, in effect, a spraying and dispersal of the syrup throughout the surrounding gas-charged water or other carbonated liquid within

mixing chamber 102. Full mixing of the syrup and the carbonated liquid is produced while both are confined within a chamber. It is important to provide such thorough mixing, since this action eliminates the necessity of manual mixing which results in undesirable freeing of entrapped carbon dioxide as results when an operator stirs the discharged fluids in a container with a spoon or other stirring implement.

It is also to be noted that when the flange 116 has returned downwardly to a point where it contacts the shoulder 112 and causes the closing of valve 104, the piston is thereby limited from further downward travel. The flow of both the syrup and the carbonated fluid is thereby terminated simultaneously.

The length of time that valve 104 is open governs the amount of carbonated fluid that will pass into the mixing chamber and through spout 40. The length of time that valve 104 is open is measured by the interval required for flange 116 to descend from its top position to that point where it has seated valve 104 in the orifice 103. The distance between the raised position of flange 116 and its lowermost position governs the volume of syrup that is dispensed through the displacement action of piston 20. Thus, the amount of carbonated fluid that is permitted to flow is directly proportionate to the amount of syrup that is dispensed from the cylinder chamber 15 by the piston. As an example, if one ounce of syrup is dispensed from the metering chamber 15 it is possible to adjust the equipment so that six ounces of carbonated fluid will be dispensed. Without changing the adjustment of the equipment, other than to lengthen the stroke of the piston by permitting flange 116 to descend slightly farther before closing valve 104, a proportionately greater amount of carbonated fluid will be also discharged. To increase or decrease the proportion of carbonated water relative to a given amount of syrup, valve 42 may be opened or closed, in which case more or less syrup will flow from the metering pump into the mixing chamber in a given period of time. Since the time element, from the beginning to the end of the flow of the syrup charge, is accompanied by movement of flange 116, the opening and closing of valve 104 will be responsive to the degree of control exercised by valve 42 on the flow of the syrup.

Although I have shown and described a specific embodiment of my invention, I am fully aware that many modifications thereof are possible. My invention, therefore, is not to be restricted except insofar as is necessitated by the prior art and by the spirit of the appended claims.

I claim:

1. In a liquid dispenser, a mixing chamber; water and syrup inlets to said chamber; a water valve controlling the flow of water under pressure to said chamber; a spring actuated piston for measuring syrup to said chamber through the syrup inlet; free return means for compressing said spring so that, on the free return of said means, said spring will actuate the piston; means operable to open said valve at the end of the spring compressing stroke; and means

for limiting movement of the piston and for closing said water valve; said free return means comprising: two connected links transmitting the operating force to one side of their axis by virtue of a stop carried by the links which limits movement of said links in one direction relative to each other, and a crank connected to one of said links for operating the same, said crank carrying a boss adaptable to engage the link connected thereto to move said link away from said stop and allow free rotation therefrom of the outward link.

2. In a liquid dispenser, a spring, a dispensing piston actuated by said spring, and free return means for compressing said spring so that on the free return of said means said spring will actuate said piston, said free return means comprising: two connected links transmitting the operating force to one side of their axis by virtue of a stop carried by the links for limiting movement of said links in one direction relative to each other, and a crank connected to one of said links for operating said links, said crank carrying a boss adaptable to engage the link connected thereto to move said link away from said stop and allow free rotation therefrom of the outward link.

3. In a liquid dispenser of the type wherein a spring pressed piston measures and forces a quantity of fluid being dispensed to a dispensing outlet, operating means for said piston comprising: a crank; two connected links for transmitting the operating force imparted through said crank to the piston, said links being adapted to transmit the operating force to one side of their axis by virtue of a stop carried by one of the links for limiting movement of said links in one direction relative to each other; and a boss between said crank and the associated link to cause movement of said link to the other side of the axis and allow free rotation of the outward link whereupon said piston is permitted free movement under the urging of its spring.

4. In a liquid dispenser, a mixing chamber, water and syrup inlets to said chamber, a water valve controlling the flow of water under pressure to said chamber, a spring actuated piston for measuring syrup to said chamber through the syrup inlet, free return means for compressing said spring so that on the free return of said means said spring will actuate the piston, said free return means operable to open said valve at the end of the spring compressing stroke, and an adjustable stop for limiting movement of the piston and for closing said water valve.

5. A mechanism for dispensing a syrup and a fluid as a mixture, comprising: a mixing chamber having a dispensing outlet, means for supplying fluid under constant pressure to said chamber, a valve for controlling the flow of fluid under pressure, a piston for supplying a measured quantity of syrup to said chamber, means for moving and potentially loading said piston, means for opening said valve in response to the movement of said piston, and means responsive to a predetermined potential unloading and movement of said piston to close said valve.

THOMAS A. HUTSELL.
